UNITED STATES PATENT OFFICE.

ADOLPH C. RECKER, OF OAKVILLE, CONNECTICUT, ASSIGNOR TO WATERBURY M'F'G CO.,
OF WATERBURY, CONNECTICUT, A CORPORATION.

PLURAL LAMP-SOCKET.

1,227,553.

Specification of Letters Patent.

Patented May 22, 1917.

Application filed March 2, 1917. Serial No. 151,960.

To all whom it may concern:

Be it known that I, ADOLPH C. RECKER, a citizen of the United States, residing at Oakville, in the county of Litchfield and State of Connecticut, have invented a new and useful Improvement in Plural Lamp-Sockets; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of a plural lamp-socket constructed in accordance with my invention.

Fig. 2 a plan view thereof.

Fig. 3 a view thereof in vertical central longitudinal section on the line 3—3 of Fig. 2.

Fig. 4 a view thereof in vertical central transverse section on the line 4—4 of Fig. 2.

Fig. 5 a detached plan view of the two-part body.

Fig. 6 a detached view in side elevation of the plug-screw shell.

Fig. 7 a detached view in elevation of the integral lamp-receptacle screw shells shown prior to their being cut and bent into final form.

Fig. 8 a corresponding view showing the integral lamp-receptacle screw shells in final form.

Fig. 9 a detached perspective view of one of the halves of the two-part body of my improved socket.

Fig. 10 a corresponding view of the complementary half of the two-part body.

Fig. 11 a perspective view of one of the modified forms which the two-part body may assume.

My invention relates to an improved plural or twin lamp-socket, the object being to produce a simple, compact, convenient and serviceable lamp-socket of the character described, constructed with particular reference to reducing the number of parts to the minimum, to avoiding the use of assembling screws and to the production of a substantial socket not readily taken apart.

With these ends in view, my invention consists in a plural or twin lamp-socket having certain details of construction and combinations of parts as will be hereinafter described and pointed out in the claims.

In carrying out my invention as herein shown, I employ an axially divided two-part socket-body comprising two complementary or half parts preferably, though not necessarily, made of insulating material such as porcelain, fiber, etc., the said parts dividing the body flatwise, as it were, or in its axial plane. One of the said parts comprises a semicircular stem 5 merging at its lower end into the center of a body 6 formed with two semicircular chambers 7 and 8 standing, as shown, substantially at a right angle to each other. The complementary part comprises a semicircular stem 9 merging at its lower end into a body 10 having two semicircular chambers 11 and 12 corresponding in size and relation to each other to the chambers 7 and 8 aforesaid, and combining therewith to form two circular chambers located within the complete two-part body and standing at an angle to each other. The said stem 9 is formed at its upper end with an integral beveled, circular crown 13 the overhanging half 14 of which fits over the upper end of the stem 5 which is made correspondingly short, as clearly shown in Fig. 4. The said crown 13 is formed with a central screw-hole 15 the upper end of which is countersunk as at 16 for the reception of the head 17 of a contact-screw 18 which extends downward through grooves 19 and 20 in the inner faces of the complementary body-parts 5 and 9. The lower end of the said screw is threaded for being screwed into the "drifted" and threaded central portion of a sheet-metal terminal-piece 21 having yielding contact-fingers 22 and 23, as clearly shown in Fig. 3.

Within the respective circular chambers produced, as described, within the two-part body, I locate integral lamp-receptacle screw-shells 24 and 25 united by a web 26 extending between their outer edges and formed upon their upper edges with corresponding arms 27 and 28 produced by centrally dividing a web 29 corresponding to the web 26 and produced in the formation of the part as shown in Fig. 7, which illustrates the mode adopted for the formation in one piece of the lamp-receptacle screw-shells 24 and 25, the same constituting one of the novel features of my improved device. The said arms 27 and 28 are soldered to corresponding arms 30 and 31 formed at opposite points upon the lower edge of a

plug-screw shell 32 which is fitted over the stems 5 and 9 of the complementary halves of the two-part body. The said arms 30 and 31 are initially formed as shown by full lines in Fig. 6, and spread apart as shown by broken lines in the said figure, by being forced into inclined slots 33 formed partly in each of the complementary body-parts where the stems 5 and 9 thereof merge into the body-portions 6 and 10 thereof as shown in Fig. 5. The said arms 30 and 31 are thus brought into position to be soldered as at 34 to the arms 27 and 28 of the lamp-receptacle screw-shells 24 and 25. The projecting outer ends of the said shells 24 and 25 receive internally threaded binding collars 35 and 36 the inner edges of which are beveled as at 37 to overlap corresponding bevels 38 formed upon the lower portions of the complementary body-parts. It will thus be seen that the complementary body-parts are bound together by means of the plug-screw shell 32 on the one hand, and by the binding-collars 35 and 36 on the other hand, the use of assembling screws being thus dispensed with.

In assembling my improved plural lamp-socket, the screw 18 carrying the terminal piece 21, together with the integral lamp-receptacle screw-shells 24 and 25, are placed in position in one of the body-parts after which the other body-part is capped over them, as it were, and the whole structure bound together by the application of the screw-shell 32 and the collars 35 and 36. When the parts are thus assembled, the arms 30 and 31 of the shell 32 are soldered as at 34 to the arms 27 and 28 of the lamp-receptacle screw-shells 24 and 25. The device as thus made, is simple, compact, and durable, and dispenses with the use of assembling screws as above stated.

Fig. 11 shows a modified form of the two-part body. In this construction, the body-parts 39 are counterparts of each, their stems 40 being alike instead of making one shorter than the other and providing the other with an overhanging ledge as shown in Fig. 4, which is at the present time my preferred construction, inasmuch as it avoids the spreading of the body-parts by the beveled head 17 of the screw 18, should tension be placed thereon, whereas in the modified form shown by Fig. 11, if tension is placed upon the screw, the tendency would be to spread the body-parts 39—39 against the shell 32.

I claim:—

1. A plural lamp-socket having an axially divided body made in two half-parts each having a stem and two corresponding chambers, and means for securing the said parts together.

2. In a plural lamp-socket, the combination with an axially divided two-part body

each of the complementary parts of which is formed with a semicircular stem and has two semicircular chambers, of a screw-plug shell encircling the said stems, two lamp-receptacle screw-shells respectively located within the circular chambers formed by the said semicircular chambers, and collars applied to the projecting ends of the screw-shells and engaging with the body-parts for holding the same together. 70

3. In a plural lamp-socket, the combination with an axially divided two-part body each of the complementary parts of which is formed with a semicircular stem, and has two semicircular chambers inclined with respect to each other, of a screw-plug shell enclosing the said stems, two lamp-receptacle screw-shells inclined with respect to each other and located within the circular chambers formed by the union of the said semicircular chambers and connected to the said screw-plug shell, and a screw centrally interposed between the said body-parts and at its inner end carrying yielding contacts positioned for engagement by lamps entered into the respective screw-shells. 80

4. In a plural lamp-socket, the combination with an axially divided two-part body each of the complementary parts of which is formed with a semicircular stem and has two semicircular chambers standing at an angle with respect to each other, the stem of one of the said parts being longer than the stem of the other part and shaped to overhang the same, lamp-receptacle screw-shells located within the chambered body, and means for securing the said body-parts together. 95

5. In a plural lamp-socket, the combination with a chambered body therefor, of a screw-plug shell, and two lamp-receptacle screw-shells standing at an angle with respect to each other, and adapted to be located within the said chambered body and made integral with each other and each furnished at a point opposite their integral connection with integral arms for their connection with the said screw-plug shell. 105

6. In a plural lamp-socket, the combination with an axially divided two-part body each of the complementary parts of which is formed with a stem and chambered, integral lamp-receptacle shells located within the said two-part body and each formed with an arm, and a screw-plug shell adapted to encircle the stems of the said parts and formed at its lower end with oppositely located fingers positioned to be connected with the respective arms of the lamp-receptacle screw-shells. 115

7. In a plural lamp-socket, the combination with an axially divided two-part body each of the complementary parts of which is formed with a stem and two semicircular chambers, and each part being formed at the 120

base of its stem with two inclined slots; of two lamp-receptacle screw-shells standing at an angle with respect to each other, located within the said chambers and each formed 5 with a connecting arm; and a screw-plug shell formed at its lower end with oppositely located arms which are entered into the said inclined slots and bent outwardly thereby into position to be connected with the re-

spective arms of the said lamp-receptacle 10 screw-shells.

In testimony whereof, I have signed this specification in the presence of two subscribing witnesses.

ADOLPH C. RECKER.
